UNITED STATES PATENT OFFICE.

WALTER SURY, OF PIETERLEN, SWITZERLAND

VISE.

Application filed March 13, 1922. Serial No. 543,415.

To all whom it may concern:

Be it known that I, WALTER SURY, a citizen of Switzerland, and a resident of Pieterlen, State of Bern, Switzerland, have invented certain new and useful Improvements in Vises, of which the following is a specification.

This invention relates to an improvement in vises.

10 One of the principal objects of the invention is to provide an improved vise which is quick acting in that the jaws may be easily and quickly adjusted to their approximate positions without necessity of continuously
15 rotating the main operating screw while at the same time not impairing the effectiveness of this screw when it is brought into action.

Another object is to provide a vise of this character which is of strong and durable construction and capable of exerting a powerful gripping action so as to hold the work or stock which it engages in proper position.

Another object is to provide a vise of this character which may be conveniently and readily manufactured, which may be easily taken down for purposes of replacement or repair and which is comparatively inexpensive to produce.

30 Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is a view in horizontal section, illustrating the preferred embodiment of the invention;

Figure 2 is a view in longitudinal vertical section, taken on line 2-2 of Figure 1;

Figure 3 is a view in transverse vertical section on line 3-3 of Figure 1, parts being omitted for the sake of illustration;

Figure 4 is an enlarged fragmentary view in transverse vertical section, taken on approximately the same line as Figure 3 and showing the two-part nut and its operating mechanism in enlarged detail:

Figure 5 is a detail view in longitudinal vertical section on line 5-5 of Figure 4; and

Figure 6 is a detail view of the nut operating mechanism in side elevation, parts being broken away for the sake of illustration.

Referring to the drawings wherein for the

sake of illustration is shown the preferred embodiment of the invention, the numeral 10 designates the base of the vise which may be suitably secured to a bench or other support. A fixed jaw, designated generally at 12 is suitably mounted on the base 10 and comprises a body portion 13, a shank 14 and a jaw face 15 of hardened steel.

A movable jaw 16 coacts with the fixed jaw and includes a hollow slide 17 arranged in an opening 13^a provided in the body portion 13 of the fixed jaw and having ribs or guides 18 which slidably fit in slideways 19 also provided in the body portion 13 of the fixed jaw. A shank 20 is integrally formed with the slide 17 and carries a hardened steel jaw face 21.

— An operating screw or spindle 25 is rotatably journaled in a bearing 26 provided therefor in the movable jaw and is provided with a collar 27 positioned to rotatably abut a shoulder 28 formed on the movable jaw and this spindle or operating screw 25 is held against longitudinal displacement by means of a stop plate 30 which is carried by the movable jaw and projects into an annular groove 31 cut or otherwise formed in the operating screw, the stop plate being releasably held in this position by means of a screw or pin 32 (see Figure 2).

A nut carrying frame, designated generally at 35 is assembled with the body portion 13 of the fixed jaw being arranged in the opening 13^a thereof, and is provided with upper and lower tongues 36 and 37 respectively which are engaged in grooves 38 and 39 formed in the upper and lower portions of the fixed jaws. The frame 35 and its ribs are formed in two sections, designated at 40 and 41, the sections fitting close together in assembly and being held in position by bolts 42 and 43 which extend through bolt holes provided therefor in the body portion of the fixed jaw and in the sections 40 and 41 respectively and which have their threaded ends engaged in threaded seats 44 and 45 provided therefor in the lower part of the body portion of the fixed jaw. In assembling the nut carrying frame with the fixed jaw, it is entered through the open rear end of the fixed jaw, the tongues 36 and 37 sliding in the grooves 38 and 39 to permit of this assembly. When properly positioned on the fixed jaw the bolts 42 and 43 are threaded home and secured to the nut carrying frame in proper position. The sec-

tions 40 and 41 of the frame are provided with bearing lugs 46 and 47 which extend inwardly and which are accommodated in the opening of the hollow slide, it being understood that the slide is not only hollow but also has one wall or face removed to accommodate these bearing lugs. A cover plate 48 is integrally formed with the section 41 and extends over to the section 40, the cover plate having a flange 49 which embraces the adjacent portion of the section 40 and this cover plate serves to enclose the mechanism carried by the frame 35 as will hereinafter more fully appear.

15 A nut, designated generally at 50 is provided and coacts with the operating screw or spindle 25 and this nut is carried by the bearing lugs 46 and 47. The nut 50 comprises two coaxing parts or sections, designated at 51 and 52, the part 52 being fitted within the part 51 and each part includes a one-half of the threaded bearing, designated at 53. The part 51 of the nut includes upper and lower plates, designated at 51^a and 51^b and curved end portions 51^c and 51^d. The plates 51^a and 51^b have lateral extensions 51^e and 51^f which are slidably received in guideways 46^a and 47^a provided in the bearing lugs 46 and 47 and in the adjacent structure of the section 40 and 41 of the nut carrying frame, as shown in Figures 1, 2 and 4, these bearing lugs serving in this manner to slidably support the parts of the nut. As shown in the drawings, the upper and lower surfaces of the part 52 slidably engage the upper and lower plates 51^a and 51^b of the part 51 and the side faces of this part 52 engages the adjacent faces of the bearing lugs whereby the part 52 of the nut is constrained to partake of its proper motions.

Operating mechanism is provided for urging the parts 51 and 52 of the nut into and out of engagement with the operating screw 25 and includes a crank shaft 55 rotatably journaled in the frame and having a pair of cranks 56 engageable with pins 57 carried on the part 51 and a single crank 58 of opposite throw with respect to the cranks 56 and engageable with a slot 59^a provided in a link 59 pivotally connected to the part 52 by a pin 60^a for imparting motion to this part. As shown in Figure 4 the link 59 has a depending rib 59^c slidably received in a guide slot 51^e formed in the lower plate 51^b of the part 51 of the nut. The curved end portion 51^c of the part 51 is also provided with a slot, designated at 51^h which is alined with or a continuation 55 of the slot 51^e and which permits the link 59 to partake of its proper movements and to be assembled and disassembled. It is obvious that when the crank shaft is turned the cranks 56 impart a rectilinear movement 60 to the part 51 and at the same time the

crank 58 being of opposite throw imparts movement in an opposite direction to the part 52.

Actuating mechanism is provided for the crank shaft and preferably comprises a lever 60 pivotally mounted on the frame as by a screw 61 and having fixed thereto a gear 62 which meshes with a gear 63 fixed to the crank shaft. The outer end of the lever is preferably weighted, as at 65, so as to normally move the lever to position to maintain the nut in operative engagement with the operating screw. It is obvious that when the lever 60 is moved its motion will be imparted to the crank shaft 55 by means of the gears 62 and 63 and this motion of the crank shaft will be effective to move the nut into and out of engagement with the operating screw. In the arrangement shown when the lever 60 is moved upwardly, the parts 51 and 52 of the nut will be moved out of engagement with the operating screw and when the lever is moved downwardly or permitted to fall downwardly these parts of the nut will be moved into operative engagement with the operating screw.

In this manner the jaws of the wrench may be quickly and readily adjusted and at the same time the operating screw may be quickly brought into action in order to impart to the jaws a powerful gripping force. The nut carrying frame may be readily disassembled from the body portion of the jaw and action may be readily had to various parts of the nut and of the operating mechanism therefor for purposes of cleaning, replacement and repair.

I claim:

1. In a vise, a fixed jaw including a body portion having an opening and provided with slideways and grooves, a movable jaw including a hollow slide having ribs operatively received in said slideways, an operating screw carried by said movable jaw and extending through the slide thereof, a nut carrying frame having tongues slidably received in the groove of the body portion and comprising sections releasably secured to the body portion, the nut carrying frame having bearing lugs arranged within the hollow slide, a two-part nut mounted on the nut carrying frame, operating mechanism for moving the parts of the nut so as to engage them with or disengage them from the operating screw including a crank shaft having cranks of opposite throw operatively connected with the parts of the nut and actuating mechanism for said crank shaft including a lever, and gearing between the lever and the crank shaft.

2. In a vise, a fixed jaw including a body portion having an opening provided with slideways and grooves, a movable jaw including a hollow slide provided with ribs operating in the slideways, an operating

screw carried by the movable jaw and extending through the slide thereof, a nut carrying frame having tongues received in the grooves and comprising sections releasably secured to the body portion and having bearing lugs, a two-part nut mounted on the nut carrying frame, one of the parts of said nut comprising upper and lower plates and curved connecting portions, the other part being slidably fitted on said plates, said plates having lateral extensions, said bearing lugs and said sections having guideways slidably receiving said lateral extensions, operating mechanism for said nut including a crank shaft journaled in said sections and having cranks of opposite throw, pins carried by said plates and operatively engageable with the cranks of one throw, a link connected to the part of the nut slidable on the plates and having a slot operatively receiving the crank of opposite throw with respect to the cranks engaging said pins, and actuating mechanism for said operating mechanism including a weighted lever pivotally connected by one of said sections and gearing between said lever and said crank shaft.

3. In a vise, a fixed jaw including a body portion having an opening provided with

slideways and grooves, a movable jaw including a hollow slide provided with ribs operating in the guideways, an operating screw carried by the movable jaw and extending through the slide thereof, a nut carrying frame having tongues received in the grooves and comprising sections releasably secured to the body portion and having bearing lugs, a two-part nut mounted on the nut carrying frame, one of the parts of said nut comprising upper and lower plates and curved connecting portions, the other part being slidably fitted on said plates, operating mechanism for said nut including a crank shaft journaled in said sections and having cranks of opposite throw, pins carried by said plates and operatively engageable with the cranks of one throw, a link connected to the part of the nut slidable on the plates and having a slot operatively receiving the crank of opposite throw with respect to the cranks engaging said pins, and actuating mechanism for said operating mechanism including a weighted lever pivotally connected by one of said sections, and gearing between said lever and said crank shaft.

WALTER SURY.
